UNITED STATES PATENT OFFICE.

RICHARD S. HAYES, OF COMMERCE, TEXAS.

BOLSTER-BEARING.

1,205,532.

Specification of Letters Patent. Patented Nov. 21, 1916.

Application filed October 26, 1915. Serial No. 58,008.

To all whom it may concern:

Be it known that I, RICHARD S. HAYES, a citizen of the United States of America, residing at Commerce, in the county of 5 Hunt and State of Texas, have invented certain new and useful Improvements in Bolster-Bearings, of which the following is a specification, reference being had therein to the accompanying drawing.

10 One object of this invention is the production of a wagon bolster which is so constructed as to be attached to a wagon body, allowing the body to rock when necessary thus providing a device which will ride 15 easily over uneven surfaces.

Another object of this invention is the production of a pair of plates which fit upon the wagon bolster in such a manner as to prevent their accidental displacement and 20 which are provided with a simple and efficient means for holding the same in their correct positions for allowing the bolster to easily operate when necessary.

With these and other objects in view this 25 invention relates to certain novel combinations, constructions and arrangements of parts as will be hereinafter fully described and claimed.

In the accompanying drawing, Figure 1 30 is a front elevation of the wagon bolster as constructed in accordance with this invention. Fig. 2 is a central longitudinal section through the assembled device. Fig. 3 is a section taken on line 3—3 of Fig. 1 looking 35 in the direction of the arrows. Fig. 4 is a top plan view of the sand bolster showing the plate mounted thereon. Fig. 5 is a bottom plan view of the rocking bolster showing the plate mounted thereon.

40 Referring to the accompanying drawing by numerals it will be seen that the invention comprises a rocking bolster 1 and a sand bolster 2. This rocking bolster 1 is provided with an even upper surface 3 which 45 will allow the same to fit snugly upon the bottom of a wagon body to which it is secured. The lower surface of this bolster 1 is curved throughout its entire length as shown clearly at 4 while the upper surface 5 of the sand bolster 2 is curved to correspond to the shape of the surface 4 of the bolster 1.

50 The plate 6 which is mounted upon the sand bolster 2 comprises an elongated body upon which are formed the flanges 7 as clearly shown in Fig. 3. These flanges are formed upon the side edges of the plate 6

so as to extend in spaced relation whereby the plate is mounted upon the sand bolster 2, the flanges will fit over said bolster in assisting in preventing the accidental displacement of the plate 6. The bolts 8 pass horizontally through the bolster 2 so as to pass through the flanges 7 thereby fixedly retaining the plate 6 in its correct position upon the upper portions of the sand bolster 2. At the central portion of this plate 6 there is formed a circular disk 9 which is constructed so as to divide the groove 10 adjacent its outer periphery, and adjacent this groove 10 there is constructed an annular extending rib 11 extending to form the depressed pocket 12 as clearly shown in Fig. 2 and an integral bushing 13 is formed upon the inner portions of the pocket 12 so as to provide the bolt opening 14. This 75 bushing 13 passes through the vertical opening 15 formed in the central portions of the sand bolster 2 for the purpose of reducing the wear thereon and thus prolonging the life of the bolster.

80 The plate 16 which is used in connection with the rocking bolster 1 is elongated similar to the plate 6 used in connection with the sand bolster 2. This plate 16 is also provided with side flanges 17 extending in parallel spaced relations so as to fit over the side surfaces of the rocking bolster 1 as shown in Figs. 1 and 3 thereby assisting in retaining the plate in its correct position upon the rocking bolster. Horizontal bolts 90 18 are passed through the flanges 17 to the bolster 1 thereby fixedly mounting the plate upon the bolster. This bolster is provided at its central portion with a socket 19 communicating with the vertical opening 20 extending therethrough. The plate 16 is provided at its central portion with a circular cup 21 which fits snugly within the socket 19 as shown clearly in Fig. 2 so that when the rocking bolster is positioned upon the 95 upper portions of the sand bolster 2 it will fit upon the circular disk 9 of the plates 6. An integral bushing 22 is formed at the central portion of the cup 21 so as to pass through the vertical opening 20 formed in 100 the rocking bolster 1 for preventing wear upon the inner portions of this opening.

105 When this device is in use, the plates 6 and 16 are mounted upon the bolsters 2 and 1 respectively and are secured in position 110 by means of the bolts 8 and 18. At this time the cup 21 will fit upon the circular

disk of the plate 6 so as to allow the opening 14 to register with the opening formed through the bushing 22, whereby a bolt may be passed therethrough. It is not deemed necessary to disclose this bolt in this application inasmuch as any suitable bolt of an ordinary construction may be passed through the bushings 13 and 22. In this manner it will be seen that the bolsters will be held in an assembled position in such a manner as to allow the same to efficiently rotate or pivot as occasion may require. It will be seen by referring particularly to Figs. 1 and 2 that the plates 6 and 16 conform in contour to the surfaces 4 and 5 of the bolsters 1 and 2, thereby fitting snugly upon the bolsters throughout their entire length. Consequently the weight of the wagon bottom upon the bolster 1 will be imparted to the bolster 2 by means of the cup 21 and the disk 9. When, however, the wagon is passing over uneven surfaces and the body begins to rock, the bolster 1 may rock upon the bolster 2 owing to the fact that the end portions of these two bolsters annularly extend in spaced relation as shown in Figs. 1 and 2. This rocking movement, however, is limited by the end portions of the plates 6 and 16 coming into engagement with each other at which time one of the beads 31 of the plate 6 will fit within one of the channels 32 of the plate 16 thereby holding the outer portions of the bolster 2 as the same is rocked. The end portions of the plate are efficiently held in their correct positions upon the end portions of the bolsters by means of the vertical bolts 33 passing therethrough as clearly shown in Fig. 2. It is, of course, obvious that the bolt which passes through the bushings 13, 22 and 25 must not be of such a thickness in its diameter as to prevent the bolster 1 from rocking, since the bolsters have curved surfaces on which the plates fit for the purpose of allowing the bolster to rock and thus take up the jarring action caused by passing over uneven surfaces. By having the countersunk pocket 12 formed in the disk 9, sufficient space is provided for the reception of any suitable lubricant whereby, when the bolsters are pivoting the inner portions of the disk 9 and the cup 21 may be lubricated for the purpose of allowing the same to freely pivot upon each other and thus reduce all frictional engagement therebetween, whereby the life of these two elements will be greatly prolonged. The fitting of the cup 21 over the annular rib 11 and into the grooves 10 will relieve the bolt passing through the bushing of practically all of the strain caused by the movement of the wagon inasmuch as the depth of the cup is of sufficient greatness as to take up the

strain caused by the movement of the wagon when the sand bolster 2 is pushed forwardly.

In the foregoing description it will be seen that a very efficient reinforcing means has been provided for the two bolsters which means being constructed so as to conform in contour with the shape of the bolsters thereby allowing the bolsters to rock when the device is passing over uneven surfaces. It will further be seen that the disk and cup formed at the central portions of the plate will engage each other so as to draw the wagon body forwardly and at the same time are provided with sufficient means for lubricating the same when in operation.

What is claimed, is:—

1. In a device of the class described, the combination of a sand bolster and a rocking bolster, protector plates carried upon said bolsters, the protector plate carried by said sand bolster provided with a circular disk intermediate its ends, said disk having an upstanding central portion, a cup formed upon the central portion of the plate carried by said rocking bolster, said cup being adapted to fit over said disk whereby the rocking bolster will be carried in its correct position above said sand bolster, bushings formed integral upon the central portion of said disk and said cup, said bushings extending through said bolsters so as to be positioned in alinement with each other whereby a bolt may be passed through said bushings for retaining said rocking bolster against accidental displacement, said plates being adapted to prevent wear upon the inner portions of said bolsters when the device is in operation.

2. In a device of the class described, the combination of a sand bolster and a rocking bolster, plates positioned upon said bolsters and provided with overhanging flanges fitting upon the side surfaces of said bolsters for holding said plates against accidental displacement, a disk formed integral upon the central portion of the plate carried by said sand bolster, said disk comprising a groove extending to form an upstanding annular rib, said rib terminating in a depressed pocket, a cup formed integral upon the central portion of the plate carried by said rocking bolster, said cup fitting over the disk formed upon the plate of said sand bolster, said pocket being adapted to contain lubricant for efficiently lubricating the inner portions of said disk and cup when the device is in operation, said disk and cup being adapted to retain said bolsters in their correct positions when in operation.

In testimony whereof I hereunto affix my signature.

RICHARD S. HAYES.
